UNITED STATES PATENT OFFICE.

JOSEPH KOBERLING, OF TULSA, OKLAHOMA.

WALL ORNAMENTATION.

Application filed December 17, 1925. Serial No. 76,057.

This invention relates to a novel wall ornamentation suitable for decorative mantel or fire-place walls, wherein a decorative, floral or geometrical design, or the like is built into the mantel or fire-place wall, and has for one of its objects to produce a well defined design character such as a floral or geometrical configuration formed of baked argillaceous material or glass articles set 10 into a backing of mortar or the like.

The invention resides in a decorative mantel or fire-place wall which employs a series of articles of floral or geometrical configuration, each article having the opposite ends 15 thereof so formed as to render them complementary to adjacent articles to permit changes in relative positions of adjacent articles to produce finished structures of different configurations.

20 The decorative articles being in the form of tiles preferably set in mortar or the like, it is also intended that the tiles may be suitably secured upon the outer face of a brick fire-place wall or the like, and said tiles may 25 further be formed of solid or hollow glass and set upon a screen wall of a box structure with illuminating means contained within the box for illuminating the glass tiles.

30 With the above general objects in view and others that will become apparent as the nature of the invention is better understood, the same consists of the novel form, combination and arrangement of parts herein- 35 after more fully described, shown in the accompanying drawings and claimed.

In the drawings, wherein like reference characters designate corresponding parts throughout the several views,

40 Figures 1 and 2 show fragmentary front elevational views of fire-place mantels for walls showing areas of different configurations to receive the decorative tile,

Figure 3 is an enlarged base view of a 45 portion of the wall showing a sectional floral spray set into the wall with the complementary ends of the sections of the floral spray permitting relative different positions thereof to produce different designs,

50 Figure 4 is a cross-sectional view taken on line 4—4 of Fig. 3 showing the decorative tile and stones set into colored mortar that is superposed upon a concrete base or the like,

55 Figure 5 is a cross-sectional view, similar

to Fig. 4 showing another form of base supporting structure for the decorative tile,

Figure 6 is a front elevational view of a portion of a wall of brick construction showing superposed thereon and in perspective, 60 one of the decorative tile,

Figure 7 is a front elevational view, partly broken away to show the method of setting up the decorative tile and the completed structure, the tiles in this form of the 65 invention being glass, and

Figure 8 is a cross-sectional view taken on line 8—8 of Fig. 7 showing a box structure having a screen cover for supporting the decorative tile and illuminating means with- 70 in the box structure.

As shown in Figs. 1 and 2, the decorative tile is associated with the front face of the fire-place walls 1 having different designs or configurations 2 and 3 as shown in Figs. 1 75 and 2 for the support and display of the decorative tile, and as the sections forming the complete tile designs may be shifted to provide varied formations, the style of openings 2 and 3 in the front wall of the fire- 80 places may be changed, or, in other words, the sections of the decorative tile may be so assembled and related to accommodate themselves to the forms of tile receiving openings in the fire-place walls. 85

The method employed in laying the decorative tile consists in first forming a concrete foundation 4 as shown in Fig. 4 upon which a fine border 5, preferably colored, is placed, in which the decorative tile 6 is partially 90 embedded as shown in section in Fig. 4. While the principal decorative feature of the mantel disclosed herein is in the form of the leaf spray and flower, it is to be understood that the same may be of any design 95 desired, such as geometrical configurations or the like. The decorative tile as shown in Figs. 3 and 6 includes a stub branch 7 having stems 8 directed outwardly thereof and carrying leaves 9 and flowers 10, the adjacent contacting ends of the stub branches 7 being complementally formed to permit different relative positions of adjacent tiles, one end of the stub branch 7 being provided 100 with a cavity 11 while the other end thereof is provided with an outwardly curved stud 12. It will, therefore, be seen that the cavity 11 forms substantially a socket for the outwardly curved end of the adjacent tile which will permit various angular posi- 105 110

tions of adjacent stub branches 7 to enable the production of completed floral designs of entirely different configurations. As a further decorative feature, pebbles 13 of 5 various sizes and dimensions are set into the colored border 5 surrounding the decorative tile for the production of a highly ornamental mantel. The decorative tile heretofore described is preferably formed of an argilaceous material that is suitably colored, thereafter glazed on its exposed face and then baked to produce a thoroughly hardened object and the fluxing of the glazes. The glazing of the tiles may embody coloring or tinted effects to render the tile highly 10 attractive.

In the form of the invention shown in Fig. 5 the base structure for the mantel includes studding 14 supporting a wooden 20 base 15 upon which building paper 16 is mounted, the metal lath or screen 17 upon the building paper being secured in position by the staples 18 and securing the body of colored mortar 5 in position. The decorative tile generally designated 6 with the stones or pebbles 13 are partially embedded in the border 5 as described in connection with Fig. 4.

A brick or stone wall is illustrated in Fig. 30 6, the blocks 19 being separated by the mortar layers 20 while tie wires 21 embedded in the decorative tile afford attaching means for the securing staples 22 that are driven into the mortar layers 20. In this form of 35 the invention, it is intended that the decorative tile be superposed upon the brick or stone wall without the necessity of embedding the same in mortar or the like.

The invention further contemplates the 40 employment of glass decorative tile, either solid or hollow, the latter being illustrated in Figs. 7 and 8 and wherein illuminating means is associated with the glass tile. As shown in Fig. 8, a metallic box 23 is set into 45 an opening 24 in the brick or plastic wall 25, said box being in the form illustrated in plan view in Fig. 7 and provided with inwardly directed flanges 26 at its open outer side. A metallic screen 27 overlies the open outer side of the box and is secured to the flanges thereof by the fastening members 28. The glass tile 6^a is formed in sections with the abutting ends of adjacent sections complementally formed as previously described 50 with reference to Fig. 3 and a filling of mortar 5 upon the screen 27 surrounds the glass tile and also has partially embedded therein, the stones or pebbles 13. As shown in Fig. 7, a switch box 29 is disposed adjacent one 55 side of the box 23 and permits the insertion and withdrawal of the flexible electric conduit 30 carrying a series of spaced electric bulbs 31 that are disposed within the box. The interior of the box being illuminated, 60 light will shine through the glass tiles 6^a and

with said tiles being colored or tinted, beautiful effects are attained.

In each form of the invention, the decorative tile disclosed is in the form of a floral spray or the like, although it is to be understood that other configurations may be employed, while adjacent contacting ends of the stub branches of the decorative tile are complementally formed to permit various relative angular positions of adjacent stub branches to obtain different completed designs.

While there are herein shown and described the preferred embodiments of this invention, it is nevertheless to be understood that minor changes may be made therein without departing from the spirit and scope thereof as claimed.

What is claimed is:—

1. A wall ornamentation including a plurality of ornamental tile sections disposed in end to end abutting relation to conjointly form an imitation of a complete object and each embodying an elongated member having one end convexed and its other end concaved, whereby the tile sections may be laid with unbroken joints in different angular relations.

2. In a wall ornamentation, a tile of the configuration of a section of a complete imitation object and embodying an elongated main member formed with complemental ends of convex and concave form respectively, whereby a plurality of the tiles may be set in end to end abutting relation and in different angular relations for cooperating to form the complete imitation object.

3. A wall ornamentation including a support, an ornamental border layer of plastic material applied to said support, and an imitation of an object embedded in and exposed at the outer surface of said border layer, said imitation object comprising a plurality of tile sections laid in end to end abutting relation.

4. A wall ornamentation including a support, an ornamental border layer of plastic material applied to said support, and an imitation of an object embedded in and exposed at the outer surface of said border layer, said imitation object comprising a plurality of tile sections laid in end to end abutting relation, each tile section being formed with complemental ends of convex and concave form, respectively, whereby the tile sections may be laid in different angular relations to follow border layers of different designs.

5. An illuminated wall ornamentation comprising a wall formed with a border recess of ornamental form, a foraminous support mounted in said recess spaced from the bottom of the latter and parallel with the plane of the wall, a border layer of plastic material covering said support, an imitation object embodying abutting light-transmit-

ting tile sections embedded in and extending through said border layer to the support, and sources of light in said recess behind the support.

5 6. A wall ornamentation including a design element formed of complemental sections, an ornamental plastic border applied

to the wall, the design sections being embedded in the border in abutting relation, and pebbles embedded in the border at the 10 sides of the design element.

In testimony whereof I affix my signature.

JOSEPH KOBERLING.
